UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

UNCOUPLING DEVICE.

Application filed June 15, 1922. Serial No. 568,525.

An object of the invention is to increase the bearing area of the operating lever upon the fulcrum, thus reducing the friction, and furthermore, to prevent its tipping and 5 wobbling which cause friction.

Another object is to prevent this same wobbling and tipping of the pin lifting lever, at the same time allowing the pin lifting lever to fulcrum laterally at its junction with the fulcrum to accommodate itself to the fore and aft movement of the coupler without transmitting any lateral movement 10 to the operating lever.

Another object is to obtain a light and 15 very strong operating lever, yet very simple to make.

The stops to limit the rotative movement of the two levers in both directions are provided by flanging the pressed steel bracket 20 upon which the fulcrum casting is mounted, or if desired, the stops may be cast integral with the fulcrum.

It will be noted that the two levers, the fulcrum and the fulcrum bracket, are all 25 very simple to make or repair and can be assembled by an unskilled person and cannot be improperly applied.

The particular formation of the operating lever makes it a shroud or hood for protecting the fulcrum and fulcrum ends of the pin lever. This construction is a protection 30 against snow, ice, gravel, dirt or the like from clogging the mechanism.

In the drawings: 35 Fig. 1 is a fragmentary elevation of a freight car with the device applied thereon.

Fig. 2 is a plan view of Fig. 1.

Fig. 3 is an enlarged plan view of the junction of the two levers showing the fulcrum. 40

Fig. 4 is an elevation of Fig. 3.

Fig. 5 shows a modified form.

Fig. 6 shows a washer used with form shown in Fig. 5. 45

Numeral 1 is the end of the car, 2 is the coupler, 3 is the coupler lock block eye, 4 is the fulcrum with large portion 5 and reduced journal portion 6 forming a shoulder for the operating lever 7. The operating lever 7 is preferably formed in an inverted U having spaced apart walls with round orifices therein forming bearings in each leg of the U to accommodate the journal 6, the engagement of the spaced apart walls with 50 the fulcrum preventing lateral swing of the

operating lever, which swing might throw the brakeman off of the lever if he was operating it with his foot. It is desirable to prevent the lateral swinging movement of the operating lever and yet to permit such movement in the pin lifting lever. The pin lifting lever 8 is also perforated to accommodate the journal 6 and is positioned between the legs of the operating lever 7 and has a normal thickness less than the distance between the walls of the operating lever so that the pin lifting lever may swing laterally to accommodate the service movements of the coupler. The lever 8 may be provided with projections 9 on either side 60 at a point opposite the fulcrum or adjacent thereto, which projections 9, coacting with the walls of the U section of the lever 7, act as a fulcrum for the pin lifting lever 8 when it swings laterally to accommodate 65 the fore and aft movement of the coupler. The cooperation of these projections 9 and walls of said U section also prevent the lever 8 from tipping and retain it in substantially 70 a vertical plane, thereby eliminating friction. The parts are held together by ordinary bolt 16 and washer 17. 75

The inverted U section of the operating lever 7 doubles its bearing area on the fulcrum 6 and also prevents it from tipping and causing friction, and also acts as a watershed and prevents accumulation of any 80 material which would clog the device. 85

The pin lifting lever 8 extends far enough into the operating lever 7 to provide 90 a heel 10 so that a downward movement of the outer end of the lever 7 causes an upward movement of the inner end of pin lifting lever at 3 and lifts the coupler lock block. 95

The fulcrum 4 is fastened to a fulcrum bracket 11 which is secured to the car by any convenient means, such as rivets 14. The lower portion is outwardly flanged to form a stop for the pin lifting lever at 12 100 and a stop for the operating lever at 13. An extreme upward movement of the lever 8 is prevented by the overlapping lever 7, which said lever 7 is stopped by flange 13 of bracket 11 or extension 15 coming in contact with 105 the flange on the bracket near point 13.

The device is held in operative position by bolt 16 and nut 17 or similar means.

The U section of the operating lever is a 110 very simple pressing operation and on ac-

count of its form is very strong in all directions, and, therefore, may be made of very light material, preferably steel plate.

Figs. 5 and 6 show a modified form where-

- 5 in washers 18 are applied which have projections or indentations 19 to serve the same purpose as lugs 9 on lever 8. The pin lifting lever 20 is then flat at the fulcrum end being merely perforated to seat on fulcrum 6.
- 10 These washers may be applied as shown or reverse thereto. Indentations may be formed in the vertical walls of the operating lever and the washers 18 omitted, which would accomplish the same purpose.
- 15 If it should be desired to reverse the position of the U sectional operating lever, then, of course, the operating lever would be extended beyond the fulcrum to operatively engage with the pin lifting lever.

20 What I claim is:

1. An uncoupling device for car couplers comprising an operating lever, a pin lifting lever, and a common fulcrum, said operating lever having two bearings on said fulcrum, 25 and said pin lifting lever mounted on the fulcrum between the bearings of the operating lever, said levers operatively connected together.
2. An uncoupling device for car couplers comprising an operating lever having two bearings on the fulcrum, a pin lifting lever mounted on the fulcrum between the bearings of the operating lever, and a common fulcrum for said levers, said pin lifting lever 30 extending beyond the fulcrum to operatively engage the operating lever.

3. An uncoupling device for car couplers comprising an operating lever, and a pin lifting lever mounted on a common fulcrum, 40 one of said levers having two bearings on said fulcrum, and the other of said levers mounted on the fulcrum between the two bearings of the first mentioned lever, said levers operatively connected together.

- 45 4. An uncoupling device for car couplers comprising an operating lever, and a pin lifting lever mounted on a common fulcrum, one of said levers having two bearings on said fulcrum, and the other of said levers mounted on the fulcrum between the two 50 bearings of the first mentioned lever, and extending beyond the fulcrum to operatively engage with the first mentioned lever.

5. In an uncoupling device for car couplers comprising an operating lever having an apertured end forming two points of bearing on a fulcrum, with another lever pivotally positioned on said fulcrum and overlapped by the apertured end of said 55 operating lever.

6. An uncoupling device for car couplers comprising a U-shaped operating lever, a pin lifting lever, and a common fulcrum, said operating lever having two bearings on 60 said fulcrum, and said pin lifting lever

mounted on the fulcrum within the U-shape and between the bearings of the operating lever, said levers operatively connected together.

7. An uncoupling device for car couplers 70 comprising a U-shaped operating lever having two bearings on the fulcrum within the U-shape, and a pin lifting lever mounted on the fulcrum between the bearings of the operating lever, and a common fulcrum for 75 said levers, said pin lifting lever extending beyond the fulcrum to operatively engage the operating lever.

8. An uncoupling device for car couplers comprising a fulcrum, an operating lever 80 with spaced apart walls having bearings on said fulcrum, a pin lifting lever mounted on said fulcrum between the said walls, the distance between said walls being greater than the horizontal width of said pin lifting 85 lever, whereby the pin lifting lever may move laterally, said levers operatively connected together.

9. An uncoupling device for car couplers comprising a fulcrum, an operating lever 90 with spaced apart walls having bearings on said fulcrum, a pin lifting lever mounted on said fulcrum between the said walls, the distance between said walls being greater 95 than the horizontal width of said pin lifting lever, whereby the pin lifting lever may move laterally, said levers operatively connected together, and means between said walls and said pin lifting lever to retain 100 said pin lifting lever in substantially a vertical plane.

10. An uncoupling device for a car coupler comprising a fulcrum, an operating lever with spaced apart walls having apertures therein engaging said fulcrum so as to provide bearings on said fulcrum and to prevent lateral swing of said operating lever, and a pin lifting lever mounted on said fulcrum between the said walls, the distance between said walls being greater than the horizontal width of said pin lifting 105 lever, whereby the pin lifting lever may swing laterally, said levers operatively connected together.

11. An uncoupling device for a car coupler comprising a fulcrum, an operating lever with spaced apart walls having apertures therein engaging said fulcrum so as to provide bearings on said fulcrum and to prevent lateral swing of said operating lever, a pin lifting lever mounted on said fulcrum between the said walls, the distance between said walls being greater than the horizontal width of said pin lifting lever, whereby the pin lifting lever may swing laterally, said levers operatively connected together, and means between said walls and said pin lifting lever to retain 110 said pin lifting lever in substantially a vertical plane.

12. An uncoupling device for a railway 115

car coupler comprising a fulcrum, an operating lever with spaced apart walls having apertures therein engaging said fulcrum so as to provide bearings on said fulcrum and to prevent lateral swing of said operating lever, and a pin lifting lever operatively connected to said operating lever and ful-

crum between said walls, the distance between said walls being greater than the normal horizontal thickness of said pin lifting lever, the thickness of said pin lifting lever being greater at said fulcrum. 10

ARTHUR E. SMALL.
